LAMINATED INSOLE FOR WELT SHOES

Filed Oct. 15, 1947

UNITED STATES PATENT OFFICE

2,548,266

LAMINATED INSOLE FOR WELT SHOES

Saul L. Katz, Rochester, N. H.

Application October 15, 1947, Serial No. 780,023

1 Claim. (Cl. 36—22)

1

This invention comprises a new and improved laminated cushion insole for welt shoes.

The general object of the invention is to provide for a welt shoe having great flexibility in its forepart and a completely cushioned bottom beneath the foot of the wearer, all without substantially increasing either the weight or the manufacturing expense of the shoe.

It will be appreciated that in leather and fabric welt shoes as heretofore constructed the forepart of the shoe has always had a tendency toward stiffness because of the multiply effect arising from the laminated sections of the insole and outsole, even though these are partially separated by a narrow band of filler. In other words, when a moderately flexible insole and a moderately flexible outsole are assembled in a welt shoe bottom the resulting structure is very greatly stiffer than either of its components.

I have discovered that when a moderately flexible insole is provided, on the face toward the outsole, with a ply or facing of cushion material which will yield readily in compression, then, under those conditions, the multiply effect is dissipated and a bottom structure results that has an unexpected and highly desirable degree of flexibility. This construction does not interfere in any way with the use of a metal shank stiffener in the shank of the shoe with the result that no departure is required from the usually practiced steps of welt shoe making beyond the furnishing of the novel insole carrying a cushion ply on its ribbed face.

An important advantage that flows from the employment of the welt insole of my invention is that the wearer is given a cushion throughout the entire length of the shoe, not only in the flexible forepart of the insole but also in the rigid shank portion where the cushion ply will be interposed between the steel shank stiffener and the foot. Thus the comfort of the wearer is improved in these two significant respects.

In the manufacture of shoes having built-in cushion bottoms considerable difficulty has been experienced heretofore on account of the fact that a cushion layer located next to the last is somewhat compressed during any proper lasting operation and when the last is withdrawn and pressure released the cushion layer will expand and reduce the effective size of the shoe. This difficulty is avoided in accordance with my invention by locating the cushion ply on the outer face of the insole, so that any tendency of the cushion ply to expand is taken up outside the area of the last and no reduction in size of the shoe takes place.

2

These and other features and advantages of the invention will be best understood and appreciated from the following description of preferred embodiments thereof, selected for purposes of illustration and shown in the accompanying drawings, in which:

Fig. 1 is a view in perspective of the leather insole blank,

Fig. 2 is a similar view of the cushion ply,

Fig. 3 is a similar view showing the two blanks united,

Fig. 4 is a plan view of a complete insole,

Fig. 5 is a plan view of an insole of alternative construction,

Fig. 6 and 7 are sectional views on the lines 6—6 and 7—7 of Figs. 4 and 5,

Fig. 8 is a sectional view through the forepart of the completed welt shoe, and

Fig. 9 is a corresponding view of the shank portion.

An insole blank 10 may be died or rounded from sole leather split or cut from any other selected moderately flexible insole stock of leather or composition, this being the ply of the insole seen inside the finished shoe. A blank 11 of cork composition or other suitable cushion material may be similarly prepared and these two plys united permanently in continuous face-to-face contact by cement 12 as suggested in Fig. 3. If a grain split is used in the blank 10 its smooth or grain face is exposed in the insole and its split or rough face is covered by the cushion ply.

The welt sewing rib is now applied to the exposed face of the cushion ply 11 as, for example, by the so-called "Prime process" suggested in Fig. 4, by presenting simultaneously a rectangular strip of core material 13 and an adhesive strip of tape 14. This may be done accurately and rapidly by machinery already available for that purpose, the tape being stuck firmly to the surface of the cushion ply 11 and set with the rib at substantially right angles to the body of the insole, or inclined slightly inwardly, and at a predetermined distance from the marginal edge of the insole, extending from the heel breast line on one side of the sole to a corresponding point on the other side of the sole.

Any form of attached sewing rib may be used within the scope of my invention, an alternative construction being shown in Figs. 5 and 7. In that instance the core 13 is covered by an adhesive sheet 15 of "Gem Duck" or the like. This takes the place of the tape 14 and extends continuously in bonded relation from edge to edge of the insole, being set as before with rib in sub-

stantially upright position. Figs. 4 and 5 therefore illustrate two illustrative embodiments of my novel insole, complete and ready for use in the production of welt shoes.

In manufacturing a shoe the welt insole is temporarily tacked and thus conformed to the bottom of the last with its ribbed face outermost and then the upper, for example, the lined upper 16, is lasted in over the feather of the insole. It is eventually secured to the sewing rib, together with the welt 17, by the stitches 18 of the inseam. The cushion ply 11 is exposed up to this stage of the shoemaking but that is now covered by a layer of the usual bottom filler which extends over the space between the sewing ribs of the insole.

Prior to the bottom filling step a steel shank stiffener 20 is attached to the exposed cushion face of the insole. This stiffener extends usually from the ball line to a point behind the heel breast line and renders the finished shoe substantially rigid throughout its shank portion. It is covered or partially covered by the bottom filler 19 as indicated in Fig. 9.

In completing the shoe an outsole 21 is laid and leveled upon the filled insole and attached by the usual lock-stitch outseam 22 to the welt 17. It will be apparent by reference to Fig. 8 that the cushion ply 11 extends continuously beneath the leather ply 10, separating it by a compressible layer from unyielding contact with the welt and the underlying outsole and substantially increasing the cushioning effect of the bottom filler 19 where that is interposed between the insole and outsole. Thus any multiply stiffening effect is broken up or dissipated and an extremely flexible bottom secured.

If preferred, the adhesive sheet 15 shown in Figs. 5 and 7 may supplement the tape 14 which forms the rib shown in Figs. 4 and 6, and in that case the sheet will be cemented across the inner margin of the insole from rib to rib and then trimmed off even with the top surface of the rib. I have found it generally advisable in using an adhesive rib to employ gem duck continuously from rib to rib to give lateral stability to the rib and insure good shoemaking and wear.

One of the problems which may sometimes occur in the process herein disclosed of manufacturing Goodyear welt shoes using the cushion welt insole is the necessity for having firm adhesion of the various units that go to make up the completed insole—that is, the laminated layers of insoling, cushion material, welt sewing rib and rib reinforcing material. It is very important that all these units be combined firmly without affecting their flexibility. Thus far, it has been

found possible to use the regular cements normally available in the trade for applying the rib to an insole and for cementing gem duck to reinforce the rib.

However, in the event that these materials should be found not sufficiently strong in their adhesion qualities, it is entirely practicable to use a cold vulcanizing cement in joining the insole layer with the cushion layer of the insole and in cementing on the rib and the gem duck reinforcement of the rib.

The nature of this cement is such that in the absence of any heat treatment of the materials that have been stuck together, but after an interval of time, the full benefit of the vulcanizing process could be effective. At the end of this time, these units would be so stuck together that the body of any one of them would have to be distorted or destroyed in the process of trying to pull them apart. This type of cement, even when treated with heat, does not reduce the flexibility of the units in which it is applied, but merely serves as a very strong sticking agent.

Having thus disclosed my invention and described in detail certain illustrative embodiments thereof, I claim as new and desire to secure by Letters Patent:

A prepared laminated insole for use with welt shoes of leather or fabric, said insole consisting of a full length ply of fibrous material, an all-over cushion ply of cork composition which is inherently resilient and will yield readily to compression and is permanently united in continuous face-to-face contact to the fibrous ply, a sewing rib disposed in direct contact with the cushion ply, and securing means comprising a covering of fabric adhesively attached to the rib and to the face of the cushion ply on both sides of the rib.
